CAMPER FOR STATION WAGONS

Eldon C. Ferguson, 9000 Douglas Ave.,
Des Moines, Iowa

Filed July 15, 1963, Ser. No. 75,813

Term of patent 14 years

(Cl. D14—3)

I claim:

The ornamental design for a camper for station wagons, substantially as shown.
